FASTENING SUPPLYING MECHANISM

Jacob C. Jorgensen, Beverly, Mass., assignor to
United Shoe Machinery Corporation, Paterson,
N. J., a corporation of New Jersey

Application January 26, 1932. Serial No. 588,960

12 Claims. (Cl. 1—6)

This invention relates to fastening supplying mechanisms such as are used for supplying fastenings in gang fastening inserting machines and is illustrated herein as embodied in a fastening supplying mechanism of the type disclosed in Letters Patent of the United States No. 1,129,882, granted March 2, 1915 on an application of Roland F. McFeely.

In supplying mechanism of the type referred to above, as heretofore constructed, a separator is provided arranged to move transversely of the ends of a plurality of raceways from which fastenings are separated thereby and delivered to a receiving member, this member being so operated as to arrive in position to receive the separated fastenings at times coinciding substantially with the delivery of the fastenings by the separator. Means is provided for imparting a plurality of reciprocating movements to the separator to separate a plurality of sets of fastenings, and the receiving member is arranged to hold a set of separated fastenings in transit until another set is separated and then to deliver to the fastening-inserting means at substantially the same time fastenings separated at different times. The separator is provided with oblique slots terminating in enlargements or eyes and as the separator moves across the ends of the raceways the fastenings move along the slots and are delivered through the eyes to the receiving member.

Fastening supplying mechanisms of this type have been in successful commercial use for many years. It has been proposed, however, to utilize mechanism of this kind for supplying a much greater number of fastenings than shown in the above-mentioned Letters Patent. For separating such a large number of fastenings it has been found desirable to shorten the slots in the separator along which the fastenings move as the separator is moved from separating position to delivery position. The fastenings, accordingly, have less distance to travel from the points of separation to the points of delivery, so that sometimes one or more of the fastenings may be delivered by the separator before the receiving member is moved into position to receive the fastenings. As a result, more than one fastening may be delivered into the same hole in the receiving member by the separator. This may cause the receiving member to jam, particularly if the head of one of the fastenings extends into one of the openings in the cap plate, so that there is a considerable loss of time by the operator in removing the misplaced fastening.

It is an object of the present invention to provide a fastening supplying mechanism of the type referred to above so organized that the above-mentioned difficulty will be obviated. As illustrated, the receiving member is provided as heretofore with a plurality of sets of fastening receiving holes for receiving the separated fastenings, and according to a feature of the invention novel means is provided, operating in timed relation to the movements of the separator, for moving the receiving member into position to receive each set of separated fastenings before the fastenings are delivered by the separator. As shown herein this means includes a rock shaft for operating the receiving member and novel mechanism for operatively connecting the rock shaft to, and disconnecting the rock shaft from, the usual crank shaft for operating the separator in each movement of the crank shaft to reciprocate the separator, so as to operate the receiving member in the desired time relation to the movements of the separator. It is a characteristic also of the construction shown that the receiving member is moved into position to deliver the first set of separated fastenings before the second set of fastenings are delivered by the separator.

With the above and other objects and features in view the invention will now be described with reference to the accompanying drawings and will be pointed out in the claims.

In the drawings,

Fig. 1 is a plan view partly in section of a fastening supplying mechanism embodying the present invention;

Fig. 2 is a vertical transverse sectional view showing the means for operating the receiving member;

Fig. 3 is an enlarged view illustrating diagrammatically the positions of the rock shaft and its operating shaft when the machine is at rest;

Fig. 4 is a similar view but showing the positions of the parts when the first series of fastenings are being delivered by the separator;

Figs. 5 and 6 are successive sectional views of the fastening receiving member and parts associated therewith;

Fig. 7 is a perspective view of the fastening supplying mechanism with parts of the structure broken away; and

Fig. 8 is a perspective view showing the operating means of the fastening supplying mechanism.

The fastening supplying mechanism herein illustrated is of the same general type as that

disclosed in the above-mentioned Letters Patent. Such mechanism comprises a raceway block 10 provided with a group of tack delivering raceways 12 to which tacks are supplied from a hopper 5 (not shown) which is oscillated to lift tacks and supply them to the raceways. A separator slide 14 is mounted for reciprocation transversely of the raceways 12 in a bracket 16 which is usually secured to the head of the machine and which 10 is arranged also to support the hopper. Secured to the separator slide 14 is a separator plate 18 provided with separating points 20 and oblique slots 22 terminating in enlargements or eyes 24 to permit the heads of the tacks to drop, after 15 separation, through openings 25 in member 26 and into tack receiving holes formed in a receiving member 28 mounted for endwise movement between the member 26 and a conductor or tack tube anchor plate 30.

20 In the illustrated construction the raceway block 10 is provided with eleven raceways and the separating mechanism is arranged to be reciprocated twice in each cycle of operation of the machine in which the mechanism is incorporated to separate and deliver twenty-two 25 tacks.

As more fully explained in the above-mentioned McFeely patent the hopper from which the tacks are supplied to the raceways 12 is oscillated once for each cycle of operations of the machine, and connected to the hopper operating shaft by means of a universal joint (not shown) is an inclined shaft 40 having a gear 42 secured to its lower end meshing with a pinion 44 formed upon a crank shaft 46, Fig. 8. The crank shaft 46 is provided with a crank 48 connected to a block 50 in a fork depending from the median portion of the separator slide 14 and from which that slide and the separator plate 18 30 receive a complete reciprocation from the oscillatory movement of the gear 42 and the hopper in one direction and a second complete reciprocation from the oscillatory movement of the gear 42 and the hopper in the other direction. Thus 40 two sets of fastenings are separated and delivered by the separator 18.

To receive the separated fastenings the receiving member 28 is provided with two sets of fastening receiving holes 36, 38 alternately arranged and in order to insure that each set of separated fastenings will be delivered into the proper holes means is provided which will now be described operating in timed relation to the movements of the separator for moving the receiving member into position to receive each set of separated fastenings before the fastenings are delivered by the separator. As illustrated this means comprises an operating shaft 52 to one end of which is secured a gear 54 the teeth of which 50 mesh with the teeth of the pinion 44. The gear 54 is provided with a greater number of teeth than the gear 42 so that the angle of oscillation of the shaft 52 is less than that of the shaft 40. Mounted above the shaft 52 in parallel relation thereto is a rock shaft 56 provided with an upwardly extending arm 58 arranged yieldingly to operate the receiving member 28 by means of spring plungers 62 as clearly shown in Fig. 2. The plungers 62 are mounted in the brackets 16 65 and are provided with reduced portions 64 passing through bushings 66 and having nuts 68 threaded upon their outer ends for adjusting the endwise positions of the plungers 62 in the brackets 16. The bushings 66 are provided with 70 collars 70 seated in slots formed in the opposite

end portions of the receiving member 28 and surrounding the reduced portions 64 of the rod 62 between the bushings 66 and shoulders formed upon the rods 62 are springs 73.

The shaft 56 is provided with a downwardly extending arm 72 diametrically opposed to the arm 58 and having a tooth-shaped end arranged to enter a single notch 74 formed in a disk 76 secured to the shaft 52, the shaft 56 accordingly being oscillated by the movement of the disk 76. The notch 74 is moved equal distances on opposite sides of the center of oscillation of the shaft 52 and its movement in each direction continues after the disk 76 has ceased to swing the arm 72, as will be evident by reference to Figs. 3 and 4. That is, the angle of oscillation of the disk 76 is greater than the angle of oscillation of the shaft 56 which carries the arms 58 and 72 during each rotation of the pinion 44 to impart a complete reciprocation to the separator 18. It will, therefore, be readily seen that the movements of the receiving member 28 into position to receive each set of separated fastenings will be completed before the fastenings are delivered by the separator 18. More particularly, as shown in Figs. 1, 3 and 100 8, the parts are in the positions which they assume when the machine is at rest. As the pinion 44 is rotated during the oscillatory movement of the gear 42 in one direction to impart a complete reciprocation to the separator 18 the 105 notch 74 is moved from the position shown in Fig. 3 to the position shown in Fig. 4. The shaft 56 is urged in a clockwise direction as viewed in Fig. 2 by a spring pressed plunger 78, Fig. 1, engaging the arm 58 so that as the notch 74 approaches the center of oscillation of the shaft 52 the arm 72 will enter the notch 74 and as the shaft 52 continues to move in a counterclockwise direction the shaft 56 will be rocked in a clockwise direction during the intermediate portion 110 of a turning movement of the shaft 52 from the position shown in Fig. 3 to the position shown in Fig. 4. Clockwise movement of the shaft 56 moves the receiving member 28 through the arm 58 and spring plunger 62 to the right until the 115 fastening receiving holes 36 are in position to receive a set of separated fastenings from the openings 25, Fig. 6. At this time the arm 72 passes out of the notch 74 after which the shaft 52 continues to rotate in a counterclockwise direction until the separator 18 delivers a set of fastenings into the holes 36. During the oscillatory movement of the gear 42 in the opposite direction to impart a second complete reciprocation to the separator 18 through the pinion 44 120 and crank 48 the shaft 52 is rotated in a clockwise direction, Fig. 2, and through the action of the arm 72 and the notch 74 the shaft 56 is rocked in a counterclockwise direction moving the receiving member 28 to the left to bring the 125 first set of holes 36 into discharging position and the second set of holes 38 into position to receive a second set of fastenings before the fastenings are delivered by the separator 18. The arm 72 is moved into the notch 74 in the clockwise movement of the shaft 56 by a spring pressed plunger 80, Fig. 1.

It will be further noted by reference to Fig. 2 that as the arm 58 is swung into substantially a central position no movement is imparted to 145 the receiving member 28, there being merely an expansion of one or the other of the previously compressed springs 73. As this occurs the separator 18 makes its rearward stroke. As the arm 58 passes a central position it begins to 150

move the receiving member 28 through one or the other of the plungers 62 and springs 73 toward its fastening receiving position as the separator 18 is beginning its fastening separating stroke, 5 this movement of the receiving member 28 being completed as hereinbefore described before the separator has been moved into position to deliver a set of fastenings.

Having thus described my invention, what I 10 claim as new and desire to secure by Letters Patent of the United States is:—

1. A fastening supplying mechanism having, in combination, a plurality of raceways, a separator arranged to separate a set of fastenings 15 from said raceways at each reciprocation thereof, means for operating the separator to separate a plurality of sets of fastenings, a member for receiving fastenings from the separator having a plurality of sets of fastening receiving holes 20 formed therein, and means for moving said receiving member in timed relation to the movements of the separator to bring the different sets of fastening receiving holes alternately into position to receive fastenings, said means being constructed to insure that each movement of the receiving member into fastening receiving position will be completed before the separator is moved into position to deliver fastenings.

2. In fastening supplying mechanism, the combination with a separator movable to separate and deliver different sets of fastenings successively, of a receiving member having a set of openings in which to receive and temporarily retain a set of fastenings delivered by the separator 35 and another set of openings arranged to receive thereafter another set of fastenings delivered by the separator, and automatic means for imparting to said receiving member movement into position to receive the second set of fastenings 40 and for completing that movement before the separator is moved into position to deliver the second set of fastenings.

3. In fastening supplying mechanism, the combination with a separator movable to separate and deliver different sets of fastenings successively, of a slide having a set of openings in which to receive and temporarily retain a set of fastenings delivered by the separator and another set of openings arranged to receive there- 50 after another set of fastenings delivered by the separator, means provided with passages leading from the separator and arranged to aline with one set of said openings when the slide is in one position and with the other set of openings when the slide is in a different position, and automatic 55 means for moving the slide, after the delivery of fastenings to one set of openings therein, to carry that set of openings out of alinement with said passages and the other set of openings into 60 alinement therewith and to complete that movement before the separator arrives in position to deliver the second set of fastenings.

4. A fastening supplying mechanism having, in combination, a plurality of raceways, a separator arranged to separate a set of fastenings from said raceways at each reciprocation thereof, means for operating the separator to separate a plurality of sets of fastenings, a receiving member having a plurality of sets of fastening receiving holes formed therein, and means for imparting a movement to the receiving member in one direction only for each complete reciprocation of the separator to bring a different set of fastening receiving holes into position to receive fastenings, said means being constructed

to operate in timed relation to the separator-operating means to complete each movement of the receiving member before the separator has been moved into position to deliver the separated fastenings.

5. A fastening supplying mechanism having, in combination, a plurality of raceways, a separator arranged to separate a plurality of sets of fastenings from said raceways by a plurality of separating movements, a member for receiving the separated fastenings delivered by the separator, and means constructed to operate in timed relation to the movements of the separator to move the receiving member into a position to receive a set of separated fastenings from the separator and then into a position to receive a second set of separated fastenings and also to deliver the set first received while the separator is separating a second set of fastenings and before it completes its movement into position to deliver the second set of fastenings.

6. A fastening supplying mechanism having, in combination, a separator, a plurality of raceways, means for operating the separator to separate a plurality of sets of fastenings from said raceways by a plurality of separating movements, a conductor plate having a plurality of fastening delivering passages formed therein, a member for receiving fastenings from the separator and delivering them to the conductor plate, and means constructed to operate in timed relation to the movements of the separator to move the receiving member into a position to receive a set of separated fastenings before the separator completes its movement into position to deliver said fastenings and then into a position to receive a second set of fastenings from the separator and to deliver the first set of separated fastenings to the conductor plate before the movement of the separator into position to deliver the second set of fastenings has been completed.

7. In fastening supplying mechanism, the combination with a separator movable to separate and deliver different sets of fastenings successively, of a receiving member having a set of openings in which to receive and temporarily retain a set of fastenings delivered by the separator and another set of openings arranged to receive thereafter another set of fastenings delivered by the separator, and automatic means for imparting to said receiving member movement into position to receive the second set of fastenings and for completing that movement prior to the delivery of the second set of fastenings by the separator, said automatic means comprising an oscillatory member movable simultaneously with the separator and having a notch therein, and another oscillatory member having an arm arranged to enter said notch and to be swung by said first-named oscillatory member during a portion only of the movement of the latter.

8. In a fastening supplying mechanism, the combination with a separator movable to separate and deliver different sets of fastenings successively, of a receiving member having a set of openings in which to receive and temporarily retain a set of fastenings delivered by the separator when said member is in one position and another set of openings arranged to receive another set of fastenings delivered by the separator after movement of the receiving member to a different position, and automatic means for moving the receiving member to its different positions in timed relation to the movements of

the separator, said automatic means comprising an oscillatory member having a notch therein and another oscillatory member having an arm arranged to enter said notch and to be swung by said first-named oscillatory member during a portion only of the movement of the latter.

9. A fastening supplying mechanism having, in combination, a member for separating a plurality of fastenings at each reciprocation thereof, a member for receiving the separated fastenings, a crank shaft for operating the separating member, a rock shaft for operating the receiving member, and means constructed to operate in time with the movements of the crank shaft for turning the rock shaft to start the movement of the receiving member into position to receive the separated fastenings substantially at the time when the separator is beginning its fastening separating stroke and to complete the movement of the receiving member before the separator has been moved into position to deliver the fastenings.

10. In a fastening supplying mechanism, the combination with a plurality of raceways, a separator arranged to separate a plurality of fastenings from said raceways at each reciprocation thereof, and a member having a plurality of sets of fastening receiving holes for receiving the separated fastenings, of means for operating the separator and receiving member constructed and arranged to impart a plurality of reciprocating movements to the separator for each reciprocation of the receiving member; said means including a crank shaft for operating the separator, a rock shaft for operating the receiving member, an oscillatory operating shaft geared to the crank shaft and arranged to receive a movement in one direction only for each movement of the crank shaft to reciprocate the separator, and connections between the operating shaft and the rock shaft whereby the latter is rotated during the

intermediate portion of the movement of the operating shaft in either direction to move the receiving member into position to receive each set of separated fastenings before the fastenings are delivered by the separator.

80

11. A fastening supplying mechanism having, in combination, a plurality of raceways, a separator arranged to separate a set of fastenings from the raceways at each reciprocation thereof, a member for receiving the fastenings movable to different positions to receive two different sets of fastenings successively, a crank shaft for operating the separator, a rock shaft for operating the receiving member, and means for operatively connecting the crank shaft to and disconnecting the crank shaft from said rock shaft in each reciprocation of the separator, said means being constructed to cause the receiving member to be moved into position to receive the second set of separated fastenings before the separator has completed its movement to separate and deliver that set of fastenings.

90

12. A fastening supplying mechanism having, in combination, a plurality of raceways, a separator arranged to separate a set of fastenings from the raceways at each reciprocation thereof, a member for receiving the fastenings movable to different positions to receive two different sets of fastenings successively, a crank shaft for operating the separator, a rock shaft for operating the receiving member, and means for operatively connecting the crank shaft to and disconnecting the crank shaft from said rock shaft in each reciprocation of the separator, said means comprising an oscillatory member movable simultaneously with the crank shaft and having a notch therein, and an arm on said rock shaft arranged to enter said notch and to be swung by said oscillatory member during a portion only of the movement of the latter.
